UNITED STATES PATENT OFFICE

WALTER SCHWEITER, OF HORGAN, NEAR ZURICH, SWITZERLAND

COP WINDING MACHINE

Application filed October 7, 1930, Serial No. 487,038, and in Switzerland November 5, 1929.

The invention relates to a cop winding machine having a winding spindle which both rotates and reciprocates.

Heretofore with cop winding machines of this kind the thread guide and its carrier remained stationary relatively to the reciprocating spindle during the formation of the pincers and was only thrust back to the left, in accordance with the application of the material onto a guide bar by means of a cone ring and a ball lock or by means of a feeler plate. The cop winding machine according to the invention is characterized by the thread guide having imparted to it an additional movement relatively to the reciprocating movement of the spindle, so that the successive layers of thread at the peak of the winding cone are axially off-set with relation to each other. This displacement of location of the winding provides a firmer binding of the layers of thread at the peak of the cop.

Two constructional examples of the invention are shown in the drawing, in which:

Fig. 1 is a vertical section and

Fig. 2 a cross section on the line II—II (Fig. 1) of one first example.

Figs. 3 and 4 are developments, and

Fig. 5 is a vertical section of a second constructional form.

1 designates the spool spindle, 2 the cam groove disc serving to reciprocate the latter and having a lift h , and 4 is the driving pulley which rotates the spindle and is connected to the spindle 1 in known manner so as not to obstruct the sliding of the spindle. 3 designates the thread guide carried by the support 5 and thrust back, by means of the usual cone ring 6 and ball lock 7, against the feeler rod 8, in accordance with the application of the material to the cop. A feeler plate of known kind may be employed in lieu of the cone ring 6.

The following device serves to effect the axial displacement of the layers of thread at the peak of the winding cone.

The shaft 9 of the cam disc is provided with a toothed part 10 which engages with a toothed part 11^a on a pin 11. The front face of this toothed part 11^a is provided with four cams 12, the development of which is shown

in Fig. 3. These cams 12 are of different heights. The feeler bar 8 which carries a roller 13 and is under the influence of a spring 14 has imparted to it by the cam 12 a reciprocating movement corresponding to the height of the cams 12. This reciprocating movement of the bar 8 is so calculated that its extreme left hand position coincides with the extreme right hand position of the spindle, so that the development of four successive thread layers may be illustrated by the diagrams as shown in Fig. 4.

This figure shows that the height of the cams 12 is such that the additional movement of the thread guide 3 produces firstly a progressive length of stroke (from point III to point I), whereupon the following thread layers have a corresponding shortening of stroke (from point I to point III). It should also be mentioned that this lengthening of the stroke only takes place at the peak of the winding cone, while there is no displacement of the stroke at the axially opposite point of reversal of the thread.

In the example according to Fig. 5 a feeler plate 6^a as is usual with pincers machines, is used in lieu of the cone ring 6.

I claim:

1. In a cop winding machine, a spindle adapted to receive a spool to be wound, means for rotating and reciprocating said spindle, a thread guide disposed adjacent the spool, and means for independently reciprocating said thread guide for displacing the ends of the successive layers of thread at the peak of the wound cop.

2. In a cop winding machine, a spindle adapted to receive a spool to be wound, means for rotating and reciprocating said spindle, a thread guide disposed adjacent the spool, means for independently reciprocating said thread guide for displacing the ends of the successive layers of thread at the peak of the wound cop comprising a cammed wheel driven by said first mentioned means, and a feeler bar yieldingly retained against said cammed wheel at one end thereof, and carrying said thread guide.

3. In a cop winding machine, a spindle adapted to receive a spool to be wound, means

for rotating and reciprocating said spindle, a thread guide disposed adjacent the spool, a cammed wheel having a plurality of regularly varying cammed surfaces synchronously driven by said means, and a bar carrying said thread guide yieldingly engaging said cammed surfaces whereby the ends of the successive layers of thread are alternately displaced progressively in an outward and inward direction at the peak of the wound cop.

The foregoing specification signed at Zurich, Switzerland, this 24th day of September, 1930.

WALTER SCHWEITER.
